UNITED STATES PATENT OFFICE.

CHARLES V. ARBOGAST, OF STOWE TOWNSHIP, ALLEGHENY COUNTY, PENNSYLVANIA
COMBINED NECK-RING AND FORMER FOR MAKING HOLLOW GLASSWARE.

1,108,964.

Specification of Letters Patent.

Patented Sept. 1, 1914.

Application filed June 15, 1912. Serial No. 703,907.

To all whom it may concern:

Be it known that I, CHARLES V. ARBOGAST, a citizen of the United States, a resident of Stowe township, in the county of Allegheny and State of Pennsylvania, have invented a new and useful Improvement in Combined Neck-Rings and Formers for Making Hollow Glassware; and I do hereby declare the following to be a full, clear, and exact description thereof.

10 My invention relates to a combined neck-ring and former for forming hollow glassware, such as tumblers, globes, shades, bottles, etc.

15 The object of my invention is to provide for the forming of the neck-portion of the article in such a way as to prevent the crazing or cracking of the glass around the upper edge of the article, and at the same time 20 so form such upper edge that the warming in, firepolishing, or grinding of the article to give the proper finish to the upper edge may be dispensed with.

25 To these ends my invention comprises, generally stated, a suitable receptacle into which a body of plastic glass is introduced, a neck-ring member formed of two hinged portions adapted to rest on said receptacle, an inside former supported by said neck-ring member in the open and closed positions of said member, and means for compacting the glass within the cavity of the neck mold and around said former, whereby 30 said neck ring member with the blank depending therefrom is inserted into a suitable blow-mold and when the article has been blown and the neck-ring member opened to remove the article, the former is still supported by said neck-ring member.

40 In the drawing Figure 1 is a vertical section of a suitable receptacle with a body of plastic glass therein; Fig. 2 is a like view with the neck-ring member and its former in position on said receptacle with the glass 45 raised to form the neck portion of the article; Fig. 3 is a view of the neck-ring and the blank carried thereby in position on the blow-mold; Fig. 4 is a plan view of the neck-ring member and its accompanying

former; and Fig. 5 is an inverted view of 50 same. Fig. 6 is a plan view of Fig. 1.

Referring to the drawing, the numeral 2 designates a suitable receptacle supported upon a table 3. The plunger 4 is contained within said receptacle, said plunger being 55 connected to the lever 5 by means of which said plunger is raised and lowered. Around the mouth of the receptacle 2 is the flange-portion 6.

The neck-ring member 7 consists of two 60 hinged portions connected by the pin 8 and provided with the handles 9. This neck-ring has formed therein the cavity 10, a portion in one member, and a portion in the other member of the ring, said cavity varying in shape according to the shape of the neck-portion of the article to be formed. As the article to be formed in the apparatus of the drawing is a shade, said neck-ring cavity is formed accordingly. The halves of 70 the neck-ring are further provided with the annular recesses 11, which are adapted to receive the projection or collar 12 of the former 13. This former 13 is inserted in position with its projection 12 engaging the 75 recesses 11 of the neck-ring halves before the pin 8 is inserted. The stop 14 on one of the neck-ring halves is adapted to engage the shoulder 15 on the other and so control the extent to which the neck-ring may be 80 opened, and in this way the former 13 is held from slipping out of the neck-ring member even when said neck-ring member is opened to its full extent as shown in Fig. 4.

The projection 12 of the former 13 may be 85 formed with an annular groove 16, and said groove registers with the cavity of the neck-ring so that a portion of the upper edge of the article is formed in the groove in projection 12. By this construction the neck-mold is sealed to prevent the escape of any glass to form a blow-over. As the projection 12 enters the recess in the neck-ring there is no outlet from the neck-mold to the atmosphere and consequently no chance for 90 a blow-over.

The former 13 has the upper flange 17 which rests upon the top of the neck ring

member and said former is further provided with the passage 18 for the admission of air in the blowing of the article, as hereinafter set forth. This flange 17 also supports the former and prevents it from dropping through the open neck-ring, when said neck-ring is opened sufficiently to release the article formed therein.

In order to bring the neck-ring member 10 into interlocking engagement with the flange portion 6 of the receptacle 2, said neck-ring member is provided with the inwardly extending flange 19 with cut away portions 20, so that when said neck-ring member is 15 applied to the receptacle 2 the openings 20 are brought into register with the flange 6 and by giving said neck-ring member a slight turn the flange 19 passes beneath the lugs 6 and prevents the upward movement 20 of the neck-ring member, and holds it securely in position during the operation of forming the blank.

The portion of plastic glass 21 from which the article is to be made is gathered on a 25 punti, or may be taken directly from the furnace, and is delivered into the receptacle 2. When the proper quantity of glass to form the article has been introduced into said receptacle, the glass is severed by shears 30 or other means, and the neck-ring carrying the former is then adjusted in position on the receptacle 2 as indicated in Fig. 2. The lever 5 is then operated either by hand or by other suitable means and is moved up to 35 the position indicated in Fig. 2, which will force the plastic glass up and into the neck-mold cavity 10 to form the upper neck portion of the article, and around the former which projects down into the blank. By 40 forcing the glass up in this manner into the neck-mold cavity, the crazing or cracking of the glass around the neck-portion is prevented as the plunger is not forced down to displace the glass as in the ordinary practice, and as a consequence the upper edge of 45 the article is smooth and even, and is finished by this operation, so that the warming in, firepolishing or grinding of the upper end of the article is obviated, thereby dispensing with the extra step in the process of 50 making such articles and the expense attending same.

When the blank has been formed in the manner indicated in Fig. 2, the neck-ring 55 member is released from the receptacle 2 and is adjusted on the blow-mold indicated in dotted lines Fig. 3 with the blank extending down within said blow-mold. The blow-pipe 22 is then brought into position to admit air to the passage 18 of the former and 60 the blank is blown out to conform to the shape of the blow-mold. The blowing takes place without withdrawing the former 13

and with said former in contact with the glass. There is no opportunity for the escape of the glass around the neck-mold to form outside of the mold the usual "blow-over," which necessitates the firepolishing or grinding of the neck of the article to give it the required smoothness and finish. 65 Furthermore as the former is not withdrawn there is an opportunity for the air to reach the glass and chill the same before the blowing operation takes place. After the article has been blown in the blow-mold, the blow-mold is opened and the neck-ring lifted off with the blown article carried thereby, whereupon by opening the halves of the neck-ring member, the article is released and may be removed to the leers. The former 70 always remains attached to the neck-ring even when the neck-ring is opened to release the article, and consequently no separate provision has to be made for the support of the former and its movement to and 75 from the neck-ring member.

I have illustrated my invention in connection with a simple form of apparatus, but wish it to be understood that I do not limit it to the particular form illustrated, as 80 this may be changed or modified in different ways without departing from the spirit of my invention. For instance, the receptacle 2 might be filled to the top and when the neck-ring member was applied the former 95 13 would force the glass up into the neck-ring cavity.

What I claim is:

1. In a combined neck-ring and former for making hollow glassware, the combination 100 of a neck-ring member composed of two hinged sections, a one-piece inside former, an interengaging connection between said neck-ring member and former, and means for controlling the extent of opening of said 105 ring member, whereby said ring-member supports said former in its open position.

2. In a combined neck-ring and former for making hollow glassware, the combination 110 of a neck-ring member composed of two hinged sections having recesses formed in their inner faces, a one piece inside former having a collar adapted to engage said recesses in the closed position of the neck-ring member, means for controlling the extent of opening of said neck ring member, whereby said neck ring member supports said former in its open position to release the article formed therein.

3. In a combined neck-ring and former 120 for making hollow glassware, the combination of a neck-ring member composed of two hinged sections, a one piece inside former having a projection engaging said neck-ring member, and means for controlling the extent of opening of said ring mem- 125

ber, whereby said ring member supports said former in its open position.

4. In apparatus for forming hollow glass articles, the combination of a suitable receptacle to receive the plastic glass, a neck-ring member composed of two hinged portions, a one-piece inside former supported directly by said neck-ring portions in the open and closed positions of said portions,

and means for forcing glass from said receptacle into said neck-ring member and around the former.

In testimony whereof, I the said CHARLES V. ARBOGAST have hereunto set my hand.

CHARLES V. ARBOGAST.
